UNITED STATES PATENT OFFICE.

HOSEA K. KRIEBEL, OF PHILADELPHIA, PENNSYLVANIA, ASSIGNOR OF ONE-FOURTH
TO FREDERICK L. KRIEBEL, OF CHICAGO, ILLINOIS.

VALVE.

1,400,172.

Specification of Letters Patent.

Patented Dec. 13, 1921.

Application filed September 17, 1920. Serial No. 410,875.

To all whom it may concern:

Be it known that I, HOSEA K. KRIEBEL, a citizen of the United States, and resident of Philadelphia, county of Philadelphia, 5 State of Pennsylvania, have invented an Improvement in Valves, of which the following is a specification.

The object of my invention is to provide a construction of steam supply valve suitable for steam heating systems employing radiators and especially adapted for controlling the supply of steam to the radiator while permitting the escape of water of condensation from the radiator into the supply 10 main, as is suitable in what is known as a one-pipe system, whether operating as a pressure or vacuum system.

More particularly, my object is to provide a control valve body having a movable 20 plug valve fitted therein, preferably with adjustable parts to control the steam passage therethrough, the body further provided with a water seal return or by-pass passage from the outlet port to the inlet port 25 at a lower level, said return passage controlled by an auxiliary valve piece movable with or actuated by the plug valve, whereby when the plug valve is in open position, the water seal is free to operate to permit of 30 water of condensation to pass in the reverse direction to the flow of the steam through the valve and when the plug valve is fully closed, the water seal or by-pass passage is also positively closed by the auxiliary 35 valve piece. In the preferred construction, the main or plug valve may be closed to an extent sufficient to shut off passage of steam and yet allow the auxiliary valve to remain open to enable the water seal to permit 40 escape of water of condensation from the outlet side, but at the same time in no wise preventing its complete sealing by the auxiliary valve when so desired and without again opening the steam passage 45 through the plug valve.

My invention also comprehends details of construction which, together with the features above stated, are fully described hereinafter and more particularly pointed out in 50 the claims.

Referring to the drawings; Figure 1 is a vertical sectional view through a valve embodying my invention; Fig. 2 is a horizontal section of the same taken on line 55 2-2 of Fig. 1; Fig. 3 is a horizontal section of the same on line 3-3 of Fig. 1, Fig. 4

is an elevation of the plug valve piece removed from the valve body; and Fig. 5 is a transverse sectional view of the same on line 5-5 of Fig. 4.

2 is the valve body, having the inlet port 3 and outlet port 4, the construction in the particular illustration showing these parts as in an angle valve suitable for use as a steam supply or control valve for steam 65 heated radiators. Interposed between the inlet and outlet portions of the valve body is a vertical plug valve seat 9 in which is fitted a tapered plug valve 6 having transverse steam ports 6^b and a cylindrical central 70 chamber 6^a with which the ports 6^b communicate. The diameter of the chamber 6^a is slightly greater than the width of the ports 6^b and the upper part of one of the ports is laterally notched as at 6^c (Figs. 4 75 and 5) through which disks 22 may be inserted into the chamber 6^a and allowed to rest one on top of the other to more or less reduce the steam passage through the plug valve piece to the extent desired to give to 80 the valve the capacity necessary when the valve is fully opened to suit requirements of large or small radiators.

The plug valve piece 6 is provided with an upward stem 7 terminating in a square 85 shaped top 16 to which is fitted a handle 8 and a pointer 15. The stem 7 extends through a stuffing box in the bonnet 10 screwed upon the body 2, the stuffing box having packing 13 and a screw gland 14 to 90 compress it about the stem. Between the bonnet 10 and the top of the tapered plug valve piece 6 is arranged a coil spring 12 for normally holding the plug valve to its seat 9. Packing 11 may be interposed between 95 the bonnet 10 and the upper rim of the body, as shown in Fig. 1.

17 is a water seal passage or trap constituting a by-pass having an upper port 18 opening into the outlet port 4 of the valve 100 body and also having a lower port 19 opening into the inlet port 3 or lower part of the valve body. The upper port 18 opens from the bottom of the outlet port 14 and the lower port 19 opens horizontally into 105 the chamber of the body immediately below the plug valve 6 and terminates in a valve seat which is controlled by an auxiliary valve piece 20 carried on the lower part of an arm or extension 21 from the 110 bottom of the plug valve 6, the said extension acting as a crank arm for operating the

valve piece 20. The operation of this auxiliary valve will now be understood, as it is apparent that when the plug valve is fully opened the valve piece 20 will be far away from the port 19; and that even when the plug valve is turned to shut off passage of steam (Fig. 2), the auxiliary valve 20 will still leave the trap of seal open. If, however, it is desired to close the trap, then the 10 plug valve is turned until valve piece 20 seats upon the valve seat at port 19 and at which time the ports 6^b of the plug valve will be fully closed. The seating of auxiliary valve 20 upon its seat acts as a stop 15 for the main valve. In this condition, the steam radiator will be mechanically closed from the steam piping. At all other positions of adjustment, the trap or water seal will permit water of condensation to drain 20 backward from the radiator into the supply main, while keeping the passage 17 sealed with water to prevent passage of steam; and it will be understood that this capacity 25 for drainage of water of condensation may be carried on whether steam is admitted through the plug valve piece 6 or not. The especial purpose of the seal 17 is to enable back-flow of water of condensation, without 30 requiring it to pass through the steam ports 6^b or in any way interfering with the regulated supply of steam to the radiator; and secondary, to prevent water hammering or 35 other noises in the valve due to the reverse direction of flow of water and steam and their interference when required to simultaneously pass through the same passages.

I have shown the construction of my improved valve in the general form preferred to meet the requirements of steam heating 40 systems and particularly those in which the water of condensation from the radiator is required to flow back through the steam supply pipe, such as in a one-pipe system, whether of the pressure or vacuum type, but 45 I do not restrict myself to the application of the valve to these uses, nor to the specific form of the details of structure shown.

It will now be apparent that I have devised a novel and useful construction which 50 embodies the features of advantage enumerated as desirable, and while I have in the present instance shown and described the preferred embodiment thereof which has been found in practice to give satisfactory 55 and reliable results, it is to be understood that I do not restrict myself to the details, as the same are susceptible of modification in various particulars without departing from the spirit or scope of the invention.

60 Having thus described my invention, what I claim as new and desire to secure by Letters Patent, is:—

65 1. A steam valve comprising a valve body having inlet and outlet ports and a main valve seat between them and also having

a water sealed passage between the inlet and outlet ports arranged as a by-pass about the main valve seat, combined with a main valve for controlling the main valve seat, and an auxiliary valve movable with the 70 main valve to control the water sealed by-pass whereby when the water sealed by-pass is closed, the main valve is also closed and the main valve may be adjusted for controlling communication between the inlet and 75 outlet ports without closing the auxiliary valve.

2. The invention according to claim 1, wherein the main valve is in the form of a plug valve having a port through it having 80 adjustable means for permitting variation of its capacity.

3. The invention according to claim 2, wherein the adjustable means for permitting variation of the capacity of the port in the 85 plug valve comprises a plurality of removable disks normally resting one upon the other and movable with the plug valve.

4. The invention according to claim 1, wherein the main valve is in the form of a 90 plug valve and is provided with a downward extension carrying the auxiliary valve to one side of its axial center of rotation.

5. The invention according to claim 1, wherein the main valve seat is a tapered 95 vertical hole opening at the bottom into the valve body chamber near the inlet and immediately above the lower port of the water sealed by-pass, and the main valve is a plug valve fitting the valve seat and having at its 100 bottom an auxiliary valve supported in the valve body chamber in horizontal alinement with the lower part of the water sealed by-pass, whereby it may be tightly closed when the main valve is also in fully closed position. 105

6. The invention of claim 5, when further distinguished by having the valves and their seats so relatively positioned that the main valve may be fully adjusted for controlling 110 flow of steam without closing the auxiliary valve but so that when the auxiliary valve is fully closed the main valve is fully closed also.

7. In a steam valve, the plug valve having 115 a central chamber, ports on opposite sides opening through its walls into the central chamber and of a width less than the width of the said chamber, one of the ports having notches on each side at its top to provide space of the full width of the central chamber, combined with a plurality of flat 120 disks adapted to be inserted into the central chamber through the notched portion of the port and to partly fill its interior space to 125 adjust the extent of the steam passage.

In testimony of which invention, I hereunto set my hand.
